(57) **CLAIM**

The ornamental design for an actuator for an aerosol spray bottle, as shown and described.

DESCRIPTION

FIG. 1 is a perspective view of an actuator for an aerosol spray bottle, and an aerosol spray bottle, showing the new ornamental design;

FIG. 2 is a front view of an actuator for an aerosol spray bottle, showing the new ornamental design;

FIG. 3 is a back view of an actuator for an aerosol spray bottle;

FIG. 4 is a left view of an actuator for an aerosol spray bottle, and wherein the right view is a mirror image thereof;

FIG. 5 is a top view of an actuator for an aerosol spray bottle; and,

FIG. 6 is a bottom view of an actuator for an aerosol spray bottle.

The broken lines shown in the drawings are included for the purpose of illustrating structural environment and form no part of the claimed design.
